CLAIM

The ornamental design for a disposable sensor attachment design, substantially shown and described.

DESCRIPTION

FIG. 1 is a perspective view of a design aspect of a disposable sensor attachment design.

FIG. 2 is a top view of the disposable sensor attachment design of FIG. 1.

FIG. 3 is a front view of the disposable sensor attachment design of FIG. 1.

FIG. 4 is a left-hand-side view of the disposable sensor attachment design of FIG. 1.

FIG. 5 is a right-hand-side view of the disposable sensor attachment design of FIG. 1.

FIG. 6 is a rear view of the disposable sensor attachment design of FIG. 1.

FIG. 7 is a bottom view of the disposable sensor attachment design of FIG. 1; and,

FIG. 8 is a cross-sectional view of the disposable sensor attachment design of FIG. 1.

The broken lines depict portions of the disposable sensor attachment design that form no part of the claim.

Also, the references to “perspective,” “front,” “back,” “side,” and “top” views in the Figures and Descriptions are not necessarily meant to require any specific orientation of the article as viewed. A disposable sensor attachment design according to the claimed design may be used in any orientation.
